(57) **CLAIM**

The ornamental design for a foldable pocket chart, as shown and described.

DESCRIPTION

FIG. 1 is a top perspective view of a foldable pocket chart in an expanded configuration showing my design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top perspective view of the foldable pocket chart in a collapsed configuration showing my design;

FIG. 10 is a bottom perspective view thereof;

FIG. 11 is a front elevational view thereof;

FIG. 12 is a left side elevational view thereof, wherein the right side elevational view being a mirror image;

FIG. 13 is a top plan view thereof;

FIG. 14 is a bottom plan view thereof; and,

FIG. 15 is a rear elevational view thereof, wherein the rear elevational view being a mirror image.

The broken line showing the foldable pocket chart in FIG. 1-4 and FIG. 7-8 are included for the purpose of showing environmental structure of cards and fasteners and form no part of the claimed design.

1 Claim, 15 Drawing Sheets
